Primary Examiner — Abraham Bahta*(74) Attorney, Agent, or Firm* — Christine Flanagan(57) **CLAIM**

The ornamental design for a greeting card with coin, as shown and described.

DESCRIPTION

FIG. 1 is perspective view of the greeting card with coin of the present invention, with closed front cover and slide panel and coin revealed.

FIG. 2 is a front view of the greeting card of FIG. 1.

FIG. 3 is a top view of the greeting card of FIG. 1.

FIG. 4 is rear view of the greeting card of FIG. 1.

FIG. 5 is a left side view of the greeting card of FIG. 1.

FIG. 6 is a right side view of the greeting card of FIG. 1.

FIG. 7 is a perspective view of the greeting card of FIG. 1, with an open front cover and slide panel and coin revealed. FIG. 8 is a perspective view of the greeting card of FIG. 1, with an open front cover and slide panel and coin inside the greeting card.

FIG. 9 is a perspective view of the greeting card of FIG. 1, with a closed front cover and slide panel and coin inside the greeting card; and,

FIG. 10 is an exploded view of the greeting card of FIG. 1. The broken line showing of portions of the greeting card with coin is included for the purpose of illustrating environmental structure and forms no part of the claimed design.
